MICHAEL LIPTAK, OF ST. PAUL, MINNESOTA

MUD-DRUM SEAL

Application filed October 15, 1928. Serial No. 312,594.

This invention relates to improvements in boiler setting constructions, and particularly relates to means applied to a bridge wall and cooperative with the mud drum to maintain a sealed relation between the two such as will prevent gases from passing from the fire chamber beneath the mud drum, thus eliminating danger of injury to the drum.

In the type of water tube boiler shown herein the vibration and expansion of boiler tubes causes lateral horizontal motions of the mud drum, and heretofore has resulted in loosening of the masonry seal between the mud drum and a portion of the bridge wall.

It is therefore an object of this invention to provide a flexible joint construction carried by the bridge wall and cooperative with the mud drum in such manner that motions of the mud drum can take place without breaking the seal, to permit gases to pass directly from the fire chamber past the bridge wall and beneath the mud drum. Another object of the invention is to provide a cap block construction for the bridge wall including elements locked in the wall structure against movement in a horizontal direction, away from the mud drum, and to provide an element socketed in this wall and engaged either directly or indirectly with the mud drum in such manner as to permit movements of the drum and element without breaking the seal between the drum and the cap block. Another object is to provide a construction in which a stepped seal is provided between the mud drum and the cap block of the bridge wall, which in conjunction with the movable structure above mentioned will also permit motions of the mud drum without breaking the seal.

Features of the invention include the broad idea of providing a movable sealing connection between the bridge wall and the mud drum, and the specific means for accomplishing this result.

Objects and advantages of the invention will appear in the description of the drawings forming a part of this application and in said drawings:

Figure 1 is a vertical transverse section

through a water tube boiler, illustrating the movable sealing construction between the mud drum and the bridge wall;

Figure 2 is a vertical sectional view substantially on line 2-2 of Figure 1;

Figure 3 is an enlarged detail horizontal section taken on line 3-3 of Figure 4, to show the herein claimed relation of the cap-block anchoring and wall re-enforcing element to the bridge and side walls of the furnace structure;

Figure 4 is an enlarged section showing the bridge wall and mud drum sealing structure, and shows a structure slightly modified over that of Figure 1;

Figure 5 is a perspective view illustrating the cap construction of the bridge wall and the means for anchoring it, and corresponding to Figure 1;

Figure 6 is a perspective view of two complementary cap elements;

Figure 7 is a perspective view of two complementary elements, which function to form a movable sealing connection between bridge wall and mud drum;

Figure 8 is a plan view of two of the complementary cap blocks, showing how they are shaped to interlock and to have the inner portions of a minimum width;

Figure 9 is a vertical elevation on line 9-9 of Figure 4, illustrating the relation of the cap and sealing elements;

Figure 10 is a view showing a modification of the movable sealing cap block construction;

Figure 11 is a perspective view further illustrating the cap block construction of Figure 10, and the means for anchoring it;

Figure 12 is a perspective view of the anchoring portion of the cap block, corresponding to the construction of Figures 10 and 11; and

Figure 13 is a view of the movable portion of the cap block illustrated in Figure 12.

Referring first to Figure 1. The invention is shown applied to that type of water tube boiler which includes a mud drum, but it is to be understood that although a most valuable application of the invention

is herein illustrated, there is no intention to limit the invention, in that it may be applied in other environments wherein a seal is to be maintained between a movable 5 and a relatively stationary element by means of a sealed element mounted to automatically adjust itself upon a relatively permanent portion of a furnace structure.

The numeral 1 generally indicates the 10 wall structure and numerals 2 generally indicate the steam drums, the steam outlet drum having a suction pipe 3, and the drums being connected by the usual pipes 4, only a few of which are shown. The mud drum is 15 indicated at 6, the connecting tubes between the mud and steam drums at 7, and the baffles at 8. The fire chamber is indicated at 9, and the bridge wall at 10. It will be understood that it is desirable to prevent 20 leakage of gas in a direction indicated by the arrows A, to protect the mud drum, prevent blistering thereof, and to prevent lowering of furnace temperature by an escape of gas in the wrong direction. The 25 proper course of the gases is generally indicated by the arrows B.

The bridge wall with the exception of the 30 cap block construction, may be of any preferred construction, but a feature of the invention herein includes the cap block construction, and the means for anchoring it, as well as the cooperative relation of the 35 movable portion of the cap block with the mud drum, providing a joint, movable without leaking, for the horizontal movements of the mud drum.

The mud drum must be so arranged that 40 it is free to move independently of the walls 1, of the furnace, since if it were immovably set in the walls, said walls would be quickly damaged, and the boiler tubes loosened. For this reason, as shown in Figure 3, the ends of the mud drum 6 extend into 45 openings formed in the wall, the diameter of the mud drum being substantially less than the diameter of the opening. Asbestos is used to close the space between the outer surface of the drum and the inner surface of the sockets or wall openings to prevent 50 escape of gas. The drum is thus free for vibration, and it is this vibration in relation to the bridge wall which in ordinary constructions breaks the seal between the wall and the drum and allows the escape of 55 gases beneath the drum.

Included as a feature of the invention, is 60 the manner of arranging a channel iron 15, as a cap-block-anchoring means, with respect to the bridge wall 10 and to the walls 1 into 65 which the ends of the bridge wall are built. Referring to Figure 3 it will be noted that the channel iron, or equivalent element providing anchoring means extends into the same walls into which the ends of the bridge 70 wall are built, and extends beyond the ends

of the bridge wall and is embedded in the furnace walls. By this means the anchoring element for the cap course of the wall is 75 protectingly arranged beneath the cap course, see Figure 4, and as will be noted it is placed at the coolest part of the bridge wall, that is in that margin or adjacent that margin opposite the fire chamber. By this means the element is arranged so that it can expand independently of the wall, and therefore so that the connection between it and the cap course blocks can be maintained under all conditions.

The height of the channel iron is substantially the height of a brick and a course of 80 bricks 16 is laid as shown to provide a top surface flush with the top surface of the flanges. A cap block 17 has an extension 18 on its lower face and this extension is engaged between the flanges of the iron as 85 shown. A layer of cement 28 is first applied to the bottom of the channel iron, to receive and embed this extension. The under surface of each block 17 engages the upper surface of the course formed by the 90 bricks 16 and thus the course of blocks 17 are made level and given a relatively large area of contact, the elements 15-18 cooperating to oppose horizontal movement of the block in a direction toward and away 95 from the mud drum 6.

The upper surface of each block is provided with a depression 21, and the depressions of the row of blocks together provide an elongated depression extending longitudinally of the wall. It is conceivable that this 100 depression may be formed in other ways.

Another feature of the invention is the shape of the cap course blocks so that they 105 can expand longitudinally of the wall without permitting passage of gas between them. Two of these elements are shown in Figure 8 in top plan. The elements might be considered T-shaped, and each provides lateral shoulders 23, which extend longitudinally 110 of the bridge wall, and which face either toward the mud drum or toward the fire box. These shoulders are cooperable as shown to permit expansion in a direction lengthwise 115 of the bridge wall but to prevent passage of the gas between the blocks into the space below the mud drum. By use of the channel iron 15 or its equivalent and by locking the blocks into the channel iron, the cap course 120 which supports the movable sealing elements forms a unit, which may be considered, for the purposes herein, as expansible lengthwise and independently of the bridge wall. For this purpose, see Figures 7 and 9, the 125 bridge wall elements 25 are shaped and connected in the manner of the cap blocks, to permit free expansion longitudinally, but prevent passage of gases between the movable bridge wall elements. The shoulders of these elements are indicated at 30. The ob- 130

ject here is to provide a movable connection between the bridge wall and the mud drum, such that the sealing relation between the wall and the movable element, and between 5 the movable element and the drum will never be broken, when the drum moves. To this end, each element 25 is provided with a curved portion 32 corresponding to the curved portion of the socket 21 of the cap 10 block. The elements are thus swingingly engaged, and element 25 can either rotate or slide with reference to the cap block. As best shown in Figure 4, when the element 25 is in sealing position, the surface 33 is in 15 contact with the drum, or with some refractory filler placed against the drum. Thus movement is provided for between the surfaces 21—32 and 33 and 6. Moreover the 20 relation of surfaces 35—36 is such that the element 25 can swing downwardly in clockwise direction upon movement of the mud drum to the right, pivoting about the curved portion 32. The element 25 has substantially only a point contact with the drum as at 25 33, the inner face of the element 25 being cut away as at 37 so that it will not engage the drum.

Another feature of the invention is the 30 formation of the cap blocks of the wall, and associated movable sealing elements. Referring to Figures 5, 8 and 9, particularly to Figure 5, it will be seen that the widths of the inner portions of the cap blocks or those 35 portions which are most exposed to the heat, are the same. Furthermore, each block is provided on each lateral vertical face with a shoulder which cooperates with corresponding opposingly faced shoulders of a contiguous block to form the sealing joint 40 heretofore mentioned. In regard to the movable sealing elements which are socketed in the upper face of the cap blocks, the widths of these blocks are equal to the corresponding portions of the cap blocks. The 45 relations of the cap blocks to the movable sealing elements are shown in Figure 9. This is an important feature of the invention, inasmuch as those faces of the cap block and sealing elements which face the fire are of a minimum width, to reduce the 50 area which is exposed to the flame, and thus to reduce erosion and cracking or splitting to the minimum.

The width of each block 17 on the fire box 55 side is four and one-half inches while the width on the opposite side varies from three and one-half to five and one-half inches. The width of each element 25 is four and one-half inches which corresponds to the width of that portion of the block 17 which 60 faces the fire box. The relative arrangement of the elements 17 and 25 is best shown in Figure 9.

The uppermost surface of the element 25 65 is spaced at least an inch below the lower-

most surface of that tube 7 which is nearest the bridge wall so that under no conditions will the tube 7 come in contact with the element 25, thus provision is made for a maximum expansion without interference with 70 the proper operation of the movable sealing elements.

As before stated, expanding and vibratory movements are communicated to the mud drum which moves in various directions, principally laterally in a horizontal direction, and when the boiler is in operation these movements ordinarily finally result in breaking of the seal. Consider the mud drum to move to the left, see Figure 4. 75 The element 25 will be rocked in counter-clockwise direction, and substantially about the surface 32 as a center, a slippage taking place between the surface 33 and the drum surface or between 33 and a layer of packing interposed between it and the drum as shown in the modification of Figure 10. However, contacts 21—32 and 33 with the drum will not be broken, but the sealed connection will always be maintained. Now 80 consider a movement in the opposite direction. The element 25 will swing in clockwise direction. In this form of the invention the surface of the mud drum occupies 85 a spaced relation with respect to the surface 39 of the cap block so that the only point of contact of the drum with what may be considered the movable portion of the bridge wall is at 33.

Although the details of construction are 90 also claimed herein, it is believed that the invention broadly consists in the provision of a movable sealing connection between the bridge wall and the mud drum, arranged 95 so that the sealing relation is maintained 100 for all motions of the drum.

In that form of the invention shown in 105 Figures 10 to 13, inclusive, the cap block 50 is formed to provide, in that surface adjacent the mud drum, a notch or step indicated at 51. The block is anchored by its cooperative relation with the channel iron 110 15^a in substantially the manner before described. The shape of the depression in the upper surface is modified to provide two straight surfaces respectively designated 115 52—53. The movable sealing element 54 has corresponding surfaces respectively 120 designated 55—56. In this instance an inter-seal is provided at 57 by a substance 125 such as asbestos or any suitable fire-proof material, and the vertical face 58 of the block 54 lies rearwardly of the surface or step 51, so that two tread portions respectively 51—59 are provided. In this case, when the mud drum moves, for example to the left, the block 54 is moved in a corresponding direction, the surfaces 52—55 cooperating to form a slide. When the mud 130 drum moves in the opposite direction, the

material 57 expands. Although the filler 57 may break contact with the vertical surfaces 58—60, yet the sealed relation is maintained at points 51—59, and when the drum 5 moves in opposite direction the filler again engages the vertical surfaces. The surfaces 51—59 also function to prevent such downward movement of the packing as will permit it to fall from its operative sealing 10 position.

I claim as my invention:

1. In combination with a furnace including walls, a bridge wall having ends extending into two of the side walls, a channel 15 iron upon the bridge wall having its channel side facing upwardly, said iron extending into the said side walls, a mud drum, blocks interlocked with the channel iron, and sealing elements swingably socketed in the 20 blocks and engaging the drum.

2. In combination with a furnace including walls, a bridge wall having ends extending into two of the side walls, a channel iron upon the bridge wall and extending into the 25 said side walls beyond the ends of the bridge wall, a mud drum, blocks interlocked with the channel iron, and sealing elements swingably socketed in the blocks and engaging the drum.

3. In combination a bridge wall and a mud drum, and a series of refractory elements arranged to engage the bridge wall and the drum and to be movable in respect to both, said elements having shoulders 35 operable to permit expansion in a direction longitudinally of the bridge wall, but to prevent passage of gas between the elements, when they are slightly separated.

4. In combination with a bridge wall having a channel across its top, and bricks in the channel locked against horizontal motion and providing a socket, a mud drum adjacent said wall, and elements swingable in the socket and resting by gravity against 45 the drum.

5. In combination with a bridge wall having a channel across its top and bricks in the channel locked against horizontal motion and providing a socket, a mud drum 50 adjacent said wall, and elements swingable in the socket and resting by gravity against the drum, said bricks being interlocked to form a sealing connection, which will permit expansion lengthwise of the wall and 55 drum but prevent gas leakage.

6. In combination a bridge wall and a mud drum, a course of refractory elements capping the top of the wall, means securing the elements to the bridge wall against 60 motions transversely thereof, said refractory elements having means sealingly interlocking them but permitting expansion lengthwise of the wall and drum without breaking the seal, and elements sealingly engaged 65 with the course of elements and movable

with respect thereto, and sealingly associated with the drum at their upper portions but not connected with the drum, but so arranged with relation to the drum that on movement thereof no thrust is transmitted 70 by the elements to the course of refractory elements, said elements having means sealingly interlocking them but permitting expansion lengthwise of the capping elements and drum without breaking the seal. 75

7. In combination with a furnace including walls, a bridge wall extending transversely between two of the walls and operatively associated therewith and an iron upon the bridge wall, a mud drum, bricks, and means locking them to the iron against movement transversely of the wall, and means sealingly engaged with the bricks and movable with respect thereto, and sealingly engaging the drum. 80

8. In combination with a bridge wall and a mud drum, a course of refractory elements arranged on the wall, and means by which said elements are secured to the wall against transverse motion, said elements having means by which they are sealingly interlocked to permit expansion lengthwise of the wall without breaking the seal, said sealing means including shoulders which slant upwardly and away from the wall and drum, and said elements cooperating to provide an upwardly faced concavity, and a course of elements sealingly engaged in the concavity and swingable therein toward and away from the drum and slanting toward the drum and sealingly associated with the drum but not connected to it and arranged so that on movement of the drum no thrust is transmitted by the elements to the wall, said elements having sealing means functionally similar to the first mentioned means and having shoulders which extend in a direction opposite to that of the first mentioned shoulders. 95

9. In combination with a bridge wall and a mud drum, two courses of refractory elements arranged on the wall one nearer and one more remote from the drum, means by which that course nearest the drum is secured to the wall against transverse motion, 100

said elements having means by which they are sealingly interlocked to permit expansion lengthwise of the wall without breaking the seal, said sealing means including shoulders which slant upwardly and away from the wall and drum, and said elements cooperating to provide an upwardly faced concavity, and a course of elements sealingly engaged in the concavity and swingable 105 therein toward and away from the drum and slanting toward the drum and sealingly associated with the drum but not connected to it and arranged so that on movement of the drum no thrust is transmitted by the elements to the wall, said elements having 110

115

120

125

130

sealing means functionally similar to the first mentioned means and having shoulders which extend in a direction opposite to that of the first mentioned shoulders.

5 In witness whereof, I have hereunto set my hand this 10th day of October 1928.

MICHAEL LIPTAK.
